(57) **CLAIM**

We claim the ornamental design for a packaging, as shown and described.

DESCRIPTION

FIG. 1 is a front perspective view of a first embodiment of a packaging showing our new design in an opened position; FIG. 2 is a rear perspective view of the packaging in FIG. 1; FIG. 3 is a front elevation view of the packaging shown in FIG. 1;

FIG. 4 is a rear elevation view of the packaging shown in FIG. 1;

FIG. 5 is a left side view of the packaging shown in FIG. 1; FIG. 6 is a right side view of the packaging shown in FIG. 1;

FIG. 7 is a top plan view of the packaging shown in FIG. 1; FIG. 8 is a bottom plan view of the packaging shown in FIG. 1;

FIG. 9 is a front perspective view of a second embodiment of a packaging showing our new design in an opened position;

FIG. 10 is a rear perspective view of the packaging in FIG. 9;

FIG. 11 is a front elevation view of the packaging shown in FIG. 9;

FIG. 12 is a rear elevation view of the packaging shown in FIG. 9;

FIG. 13 is a left side view of the packaging shown in FIG. 9;

FIG. 14 is a right side view of the packaging shown in FIG. 9;

FIG. 15 is a top plan view of the packaging shown in FIG. 9;

FIG. 16 is a bottom plan view of the packaging shown in FIG. 9;

FIG. 17 is a front perspective view of the packaging of FIG. 1 in a closed position;

FIG. 18 is a rear perspective view of the packaging in FIG. 17;

FIG. 19 is a front elevation view of the packaging shown in FIG. 17;

FIG. 20 is a rear elevation view of the packaging shown in FIG. 17;

FIG. 21 is a left side view of the packaging shown in FIG. 17;

FIG. 22 is a right side view of the packaging shown in FIG. 17;

FIG. 23 is a top plan view of the packaging shown in FIG. 17;

FIG. 24 is a bottom plan view of the packaging shown in FIG. 17;

FIG. 25 is a front perspective view of the packaging of FIG. 9 in a closed position;

(Continued)

FIG. 26 is a rear perspective view of the packaging in FIG. 25;

FIG. 27 is a front elevation view of the packaging shown in FIG. 25;

FIG. 28 is a rear elevation view of the packaging shown in FIG. 25;

FIG. 29 is a left side view of the packaging shown in FIG. 25;

FIG. 30 is a right side view of the packaging shown in FIG. 25;

FIG. 31 is a top plan view of the packaging shown in FIG. 25; and,

FIG. 32 is a bottom plan view of the packaging shown in FIG. 25.

The shade lines shown represent surface shading and not surface ornamentation, color, or material type. The dot-dashed boundary lines shown do not form part of the claimed design. The bounds of the claimed design are defined with dot-dashed boundary lines when the boundary does not exist in reality in the article embodying the design. The illustrated designs extend to the boundary but do not include the boundary.
